UNITED STATES PATENT OFFICE.

FRIEDRICH ROSCHER, OF WASHINGTON, DISTRICT OF COLUMBIA.

COMB.

Application filed March 1, 1923, Serial No. 622,120. Renewed January 31, 1924.

To all whom it may concern:

Be it known that I, FRIEDRICH ROSCHER, a citizen of Germany, residing at Washington, in the District of Columbia, have invented certain new and useful Improvements in Combs, of which the following is a specification, reference being had to the accompanying drawings.

This invention relates to certain improvements in combs and it is an object of the invention to provide a novel and improved device of this general character wherein the teeth thereof are formed in a manner to substantially eliminate scratching of the scalp or undue friction being imposed thereon.

The scratching and rubbing of the scalp, as by the thin pointed teeth of ordinary combs results in the hardening or toughening of the skin and which action results in retardation of the flowing of blood through the scalp whereby the hair roots do not receive requisite nourishment. It is a further object of my invention to provide a comb which avoids these disadvantages.

Another object of the invention is to provide a novel and improved comb wherein the teeth are formed in a manner to provide a cushion of hair between the scalp and the teeth as the comb is drawn through the hair and thereby providing a cushion which prevents scratching of the scalp and friction or rubbing action direct upon the scalp.

The invention consists in the details of construction and in the combination and arrangement of the several parts of my improved comb whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in perspective illustrating a comb constructed in accordance with an embodiment of my invention;

Figure 2 is a plan view of a blank from which the comb as illustrated in Figure 1 is produced;

Figure 3 is a view in perspective illustrating a comb constructed in accordance with a further embodiment of my invention;

Figure 4 is a view in perspective illustrating a comb constructed in accordance with another embodiment of my invention.

As illustrated in Figures 1 and 2 of the accompanying drawings, my improved comb is produced from a blank B of preferred material possessing a requisite degree of rigidity yet capable of being readily flexed. The blank B as herein disclosed is oblong in form and provided at its transverse center with a series of longitudinally spaced recesses or slots 1, said slots or recesses being disposed transversely of the blank. One longitudinal marginal portion of the blank B is provided with a reverted flange 2, a lip a of which being inwardly disposed.

In producing the comb the blank B is returned or flexed transversely thereof with a marginal portion thereof engaged inwardly of the lip a of the flange 2 resulting in the formation of the teeth or strips 3. As is clearly illustrated in Figure 1 each of the teeth or strips 3 is relatively wide and flat and in side elevation is oval in form with its free end outwardly disposed. To further maintain the assembly of the comb suitable fastening means, as generally indicated at 4, may be employed.

As the comb is drawn through the hair the outer ends of the teeth or strips 3 will pass over the scalp without scratching and with a minimum of friction upon the scalp. This action is due to the fact that the teeth or strips 3 will pass over a small percentage of the hair whereby a cushion is provided. This advantageous action of the teeth or strips 3 is also further facilitated in view of the fact that each of the same is relatively wide.

As illustrated in Figure 1 the longitudinal marginal portion of the blank or body B may be readily attached or detached. This is of particular advantage because when said marginal portions are detached the blank or body B may be flattened out in order to facilitate cleansing and whereby the comb is maintained in a highly sanitary condition.

The embodiment of my invention as illustrated in Figure 3 is substantially the same as hereinbefore described with the exception that the body B' and the teeth or strips 3' are of greater thickness and that the longitudinal marginal portions of the blank or body B' are permanently connected, such connection being effected by rivets 5 or otherwise as may be preferred.

Figure 4 illustrates an embodiment of my invention wherein the teeth 3^a are solid yet having a peripheral contour substantially the same as comprised in the two forms of my invention hereinbefore referred to.

From the foregoing description it is thought to be obvious that a comb constructed in accordance with my invention is particularly well adapted for use by reason of 10 the convenience and facility with which it may be assembled and operated, and it will also be obvious that my invention is susceptible of some change and modification without departing from the principles and spirit 15 thereof and for this reason I do not wish to be understood as limiting myself to the precise arrangement and formation of the several parts herein shown in carrying out my invention in practice except as hereinafter 20 claimed.

I claim:—

1. As a new article of manufacture, a comb, the teeth of which being each substantially oval in form with the wider end outwardly disposed.

2. As a new article of manufacture, a comb, the teeth of which each being substantially oval in form with the wider end outwardly disposed, the periphery of each of 30 the teeth being relatively broad.

3. As a new article of manufacture, a comb, the teeth of which each being substantially oval in form with the wider end outwardly disposed, the periphery of each of 35 the teeth being relatively broad and flat.

4. As a new article of manufacture, a

comb comprising a body provided at its central portion with a series of longitudinally spaced and transversely disposed slots, said body having its longitudinal portions in 40 overlying relation, the line of fold intersecting the slots whereby a plurality of strips are provided, each of said strips being substantially oval in form with the wider end outwardly disposed.

5. As a new article of manufacture, a comb comprising a body provided at its central portion with a series of longitudinally spaced and transversely disposed slots, said body having its longitudinal portions in 50 overlying relation, the line of fold intersecting the slots whereby a plurality of strips are provided, each of said strips being substantially oval in form with the wider end outwardly disposed, the periphery of each of 55 the strips being relatively broad.

6. As a new article of manufacture, a comb comprising a body provided at its central portion with a series of longitudinally spaced and transversely disposed slots, said 60 body having its longitudinal portions in overlying relation, the line of fold intersecting the slots, whereby a plurality of strips are provided, each of said strips being substantially oval in form with the wider end 65 outwardly disposed, and means for holding the longitudinal marginal portions of the body in overlying relation.

In testimony whereof I hereunto affix my signature.

FRIEDRICH ROSCHER.
